FLOWMETER

Frank W. Thomas, Pasadena, Calif., assignor to
Allen Electric & Equipment Co., Kalamazoo,
Mich.

Application August 12, 1937, Serial No. 158,713

28 Claims. (Cl. 73—209)

This invention relates to improvements in flowmeters.

This invention relates to flowmeters primarily for use in measuring the flow of fuel to internal 5 combustion engines when employed in their various uses. It has for its objects:

First, to produce a new and improved flowmeter.

Second, to produce such a device which is suitable 10 for use in internal combustion engine work to determine the amount of fuel employed over a given period of time.

Third, to produce such a device which is extremely accurate and which may be made quite 15 inexpensively.

Fourth, to provide such a device in which the flow of the fluid to the internal combustion engine provides all the essential power for operation 20 without substantially interfering with the regular flow of the fuel and which can be operated with a minimum amount of said fuel, so that the operation of the engine in starting will not be interfered with.

Fifth, to provide such an apparatus in which 25 the flow of fuel to the engine is utilized through diaphragm means.

Sixth, to provide such a device in which reductions in the effective area of the diaphragm are compensated for.

Seventh, to produce a spring means suitable 30 for use in opposing the action of the diaphragm and for compensating for reduction in effective area of the diaphragm as it advances which device is substantially free from friction.

Further objects and advantages pertaining to 35 details and economies of construction and operation will appear from the description to follow. Preferred embodiments of my invention are illustrated in the accompanying drawings, in which:

Fig. 1 is a front elevational view of my improved apparatus.

Fig. 2 is a front elevational view of the working portion of my apparatus partly in section to 45 show certain of the working mechanism.

Fig. 3 is a bottom plan view of the apparatus taken on line 3—3 of Fig. 2.

Fig. 4 is a detail sectional view taken on line 50 4—4 of Fig. 2.

Fig. 5 is a detail sectional view of the apparatus taken on line 5—5 of Figs. 2 and 3.

Fig. 6 is a fragmentary view taken from the right hand side of Fig. 2, portions being broken 55 away to show the operating mechanism and

showing the variable orifice of the meter in open position.

Fig. 7 is a detail sectional view taken on line 1—7 of Figs. 2, 4 and 5.

Fig. 8 is a detail sectional view taken on the 5 line 8—8 of Fig. 6.

Fig. 9 is a perspective view of the working mechanism of my device with the outer covering and the dial removed.

Fig. 10 is a rear view of my apparatus with 10 the outer covering removed and with the back of the casing removed to show the arrangement of the diaphragm and the spring which opposes the movement of the diaphragm.

Fig. 11 is a detail perspective view of a portion 15 of the indicator mechanism.

Fig. 12 is a detail perspective view showing more of said indicator operating mechanism.

Fig. 13 is a detail sectional view showing a 20 modified form of toggle joint for use in connection with the spring mechanism for opposing movement of the diaphragm, showing the apparatus in full line in one position and in dotted lines in one of its other positions.

Referring to the drawings, 1 is an outer covering having a handle 2 for transporting the same. The working parts of the mechanism are enclosed within this outer covering to permit ease in transportation and to protect the operating parts and to improve the appearance of the device. The operating mechanism of the device consists of a casing 3 formed of two halves 4 and 5 which are sealed together with a gasket 6 and suitable screw fastening means 7. A main fuel passage for the fuel to be metered is indicated generally at 8. At the up-stream end of this passage 8 is an inlet 9 which is provided with a suitable nipple 10 and a rubber hose connection 11 for connection to the gasoline pump or source of supply for operating an internal combustion engine to be tested. A suitable filter 190 is disposed in the inlet 9 to strain the dirt, lint, etc. from the gasoline. I prefer to use for this tubing a synthetic rubber material sold commercially under the trade name "Duprene." The outlet 12 at the down-stream end of passage 8 is provided with a nipple 13 and a tube 14 similar to the tube 11 which connects the apparatus with the fuel line leading to the carburetor of the 40 internal combustion engine to be tested.

45 Disposed in the passage 8 is a variable orifice 15 consisting of a jet 16 screw threaded at 17 in the passage 8 and having a taper extended with the restricted end in the passage 8. A ball 18 55

serves as a valve and is movable into and out of the tapered jet 16 to vary the size of the orifice. The ball is mounted on a suitable resilient wire 19 and is of a size to pass freely through the 5 tapered jet 16. I prefer to have the ball slightly smaller than the smallest portion of the tapered passage through the jet 16 so that a slight amount of fuel may always pass through the jet.

10 Disposed within the casing 3 is a diaphragm 20 made of any suitable flexible material. The diaphragm is formed of a very thin substantially friction-less material sold commercially as "Neoprene". This is very thin aeroplane cloth 15 treated with the synthetic rubber product "Duprene" above referred to. In my device, I have found that a diaphragm five inches in diameter is substantially the proper size for the purpose intended. The diaphragm 20 divides 20 the chamber 3 into an up-stream chamber 21 and a down-stream chamber 22. A restricted passage 23 extends from the portion of passage 8 up-stream from the jet 16 to the up-stream chamber 21. The down-stream chamber 22 communicates directly at 24 with the jet 16 down-stream from the ball 18. The passages 23 is 25 restricted to dampen the movements of the diaphragm which might result from uneven operation of a fuel pump, road vibrations or any other 30 reason and in running a road test with my apparatus the fuel is preferably admitted to the chamber 21 only through the restricted passage 23.

In operating my device on the floor for testing stationary engines or for testing automobile engines or the like, or where dampening is not necessary, I admit fuel to the chamber 21 through an additional passage 25 which is controlled by a needle valve 26 having an outlet 27, 35 a valve seat 28, a valve body 29 screw threaded at 30 to the valve casing 31 and provided with a knurled knob 32. When this valve is open, additional fuel may be admitted to the up-stream chamber 21 thereby eliminating the dampening 40 effect and making the instrument more responsive to very slight variations.

The chambers 21 and 22 are restricted and are kept as small as possible for a purpose to be later explained.

50 The rear half 5 of the casing 3 is provided with a flat portion 33 disposed as close to the diaphragm 20 as is possible without interfering with the operation thereof and close enough to serve as a stop limiting the movement of the 55 diaphragm. Raised portion 34 is provided on the rear half 5 of the casing 3 to accommodate spring mechanism 35 for opposing the movement of the diaphragm into the the chamber 22. In the form of invention shown in Figs. 1-12, this 60 mechanism consists of a toggle 36 having a first arm 37 and a second arm 38. The joint of the toggle consists of a cam surface 39 on the toggle arm 37 and a cam surface 40 on the toggle arm 38 connected by a flexible strap 41 which is fastened at 42 at one end of cam 39 and extends between the cams 39 and 40 and is fastened at 43 at the opposite end of cam 40. The strap 41 is so disposed that it connects the toggle arms and makes the spring pressure exerted on the 65 toggle arms effective to oppose movement of the diaphragm 20 into the chamber 22. The free end 44 of toggle arm 38 is held by a strap 45 clamped by a screw 46 thereto and clamped by a screw 47 to the casing 3. This strap is sufficiently resilient to permit movement of the free

end 44 of toggle arm 38 toward and away from the pivot point of the toggle arm 37 and still holds the end 44 against any rotary movement about the pivot point of the toggle arm 37.

The toggle mechanism and the mechanism for controlling the size of the variable orifice are closely tied together. A lever 48 is provided extending through the chamber 22 and opposite the diaphragm 20. The resilient wire 19 carrying the ball 18 is fixed to the end of this lever 10 and is movable thereby. The lever has a pivot point 49 which serves also as the pivot point for the toggle arm 37 which is fastened by screws 50 to the lever 48. An arm 51 extends from the toggle arm 37 and a tension spring 52 is connected by a metal strap 53 to the end of the arm 51. A metal strap 54 connects the other end of the spring to the toggle arm 38. The metal straps 53 and 54 are substantially two-thousandths of an inch thick and the strap 45 20 is made of similar material. It will be apparent that this mounting is substantially friction-less because the bending of the straps 45, 53 and 54 offers substantially no frictional resistance.

In the preferred construction, the free end 44 25 of the toggle arm 38 is bent upwardly as shown in Figs. 5 and 6 and the strap 54 is fastened to the toggle arm 38 at the point 55 which is disposed to one side of the axis of the toggle arm 38 which passes between the extreme end of the 30 toggle arm 38 and the point of contact of the cam 40 with the cam 39. This point 55 is disposed between the axis and the diaphragm 20 and the result is that when the toggle arm 38 is moved in a counter-clockwise direction, as 35 viewed in Fig. 5, the point 55 moves toward the arm 51, thereby reducing the effective length of the spring 52. The effective length of the spring 52 is also controlled by the cams 39 and 40 which are so shaped that as the toggle moves in either 40 direction the distance between the free ends of the toggle arms 37 and 38 is controlled with a consequent control on the stretching of the spring.

A thrust member 56 extends from the diaphragm 20 to the toggle arm 38. This member is provided with a reduced end 57 extending through an aperture in the toggle arm 38. A metal diaphragm plate 58 is riveted to the diaphragm with rivets 59 and the thrust member 56 is riveted to said plate at the point 60.

The lever 48 is provided with a novel pivot means which permits the end of the lever to extend out of the down-stream chamber 22 to provide means for actuating the indicating mechanism, as will be later explained. A fork 61 is provided on the end of the lever provided with adjustable pivot bearings 62, riding in suitable seats 63 mounted on the casing 3. I prefer to make these seats as friction-less as possible 60 and prefer to use ball bearing or jewel mountings which are not shown in detail since they do not form any part of this invention. The fork 61 is mounted on the end of the lever 48 which passes through an aperture 64 in the 65 wall of the down-stream chamber 22. By providing the fork member 61 on the end of the lever 48, I cause the pivot point 49 of the lever 48 to fall in the aperture 64. A diaphragm 65 is sealed to the lever 48 and extends across the aperture and is sealed by a suitable ring 66 with screws 67 extending into the casing, providing a seal against loss of fluid from the chamber 22 and permitting substantially friction-less movement of the lever 48 and the transmission of the move- 70

ment of lever 48 to the outside of the casing 3.

Mounted on the outer end of the lever 48 is an arm 68 having at its end a ball 69 to form a universal connection with the indicating mechanism. An arm 70 extends from the other side of the lever and is provided with a set screw 71 forming a stop against the casing 3. A counterweight 171 is mounted on the outermost end of lever 48.

The indicating mechanism consists of a dial 72 which has on it indicia 73 indicating gallons per hour flow through the meter. These indicia are indicative of gallons per hour, but it will be apparent that when I refer to gallons per hour I have reference to any unit of measure for any unit of time and that gallons per hour are merely illustrative. Indicia 74 are provided to indicate the miles per gallon obtained in an automobile or the like which is being tested by my apparatus, and by properly adjusting the indicating mechanism it is possible to obtain a direct reading in miles per gallons for any given speed of operation of the vehicle. It will be apparent that the reference to miles per gallon is illustrative only and that when I refer to miles per gallon I do not necessarily limit myself to these particular units of measure.

The dial is provided with a hand 75 which is mounted on a shaft 76 bearing a pinion 77 and having a watch spring 78 thereon to reduce vibration of the hand in the operation by eliminating lost motion in the gearing. A curved rack 79 is pivoted on a shaft 80 in engagement with the pinion 77. An arm 81 extends from the rack 79 to engage a connecting link 82. The connecting link 82 is a metal strap bored at 83 to provide a seat for the ball 69. The end of the strap is turned back as at 84 to clamp the ball 69 to the seat 83 providing a universal connection, and a member 85 is provided to prevent dislodgment of the link from engagement with the ball 69. The link 82 is provided with a slot 86 fitting over the lever 81. A notch 87 is provided in the end of the link 82 and a spring 88 is fastened to the rack 79 fits in the notch 87 to hold the link 82 and the lever 81 in contact, as indicated in detail in Fig. 11.

The hand operating mechanism is mounted on a cross strap 89 which is pivoted on a screw 90. Adjustment is provided with the slot 91 and screw 92 at one end of the strap and with a slot 93 and a cam 94 provided with a slotted head 95 at the other end of the strap, permitting the mechanism to be adjusted to or away from the arm 68 of the lever 48. Movement of the lever 68 to or away from the hand operating mechanism causes the hand to rotate on the dial through the action of the lever 81 and the spring 88 on the end of the link 82. A curved portion 96 is provided on the upper surface of the lever 81 and the end of the slot 86 rides on this curved portion. The curve of the curved portion 96 is a radius equal to the length of the link 82 between the ball 69 and the top end of slot 86. This provides for a shifting of the link 82 along the lever 81 without causing any movement of the pointer over the dial. This permits the ratio of movement between the lever 68 and the pinion 77 and the hand 75 borne thereby to be varied so that the indicating apparatus can be adjusted to read miles per gallon at any given rate of speed. Means are provided for adjusting the position of the link 82 along the lever 81. These consist of a tension spring 97 anchored on an arm 98 at one

end and fastened to the link 82 at 99. A connecting member 100 on the other side of the link 82 connects to the end 101 of the arm 102 of bell crank lever 103 which is pivoted at 104 and the arm 98 is pivoted to the same end 101. The other arm 105 of the bell crank lever has a cam follower portion 106 which engages a cam 107. A worm gear 108 is provided in operative engagement with the cam 107 and a worm 109 in engagement with the worm gear 108 is mounted 10 on a shaft 110 which is provided with an adjusting knob 111. A dial 112 is mounted on the shaft 113 which carries the cam 107 and indicia 114 indicate in miles per hour the relative position of the link 82 and the arm 81. It will be apparent 15 that miles per hour is merely illustrative and that I do not intend to be limited to the particular units of measurements selected. A spring 115 is provided connected to the arm 102 of bell crank lever 103 and to the casing at 116 to assist in the 20 movement of and the holding of the link 82 in adjusted position.

In Fig. 13 I show a modification of the joint of the toggle 36. The toggle arm 138 corresponds to the arm 38 of the toggle shown in Figs. 1-12. 25 The toggle arm 137 corresponds to the toggle arm 37. On the toggle arm 137 I provide a circular member 139 corresponding to the cam 39. A flexible strap 141 is fastened to the member 139, extends therearound and between the member 30 139 and the end of the toggle arm 138, and is fastened at 143 to the end of the toggle arm 138. This arrangement of parts serves as a toggle joint operated substantially the same as the toggle joint shown in Figs. 1-12. A member 117 is 35 mounted adjacent the member 139. The strap 153 corresponds to the strap 53 to which the spring is attached and when the device rotates to the position indicated in dotted lines, the member 117 engages the strap 153, bending it to the 40 dotted line position. This tends to increase the force of the spring in opposition to the movement of the diaphragm and is provided to compensate in certain instances for variations in flow due to 45 certain jet characteristics. This is used in automobile testing apparatus where testing at higher speeds is desired.

The operation of this device is as follows: The meter is connected in the fuel circuit of the internal combustion engine to be tested. The upstream tube 11 is connected to the fuel supply and the tube 14 is connected to the line so that it will communicate with the carburetor and the engine. The engine is then started and the fuel flows through the inlet 9 through the jet 16 and 55 out at the outlet 12. A small amount of fuel passes through the passage 23 to the up-stream chamber 21. Fuel also flows into the chamber 22, filling it. It will be noted that when the device is operated some air will be trapped in the 60 chamber 21 because the passage 23 opens into the chamber at a point below the top of the chamber 21. This is not only not objectionable, but is very desirable in smoothing out pump pulsations and the like.

The diaphragm 20 is made purposely of such size that it will be able to provide sufficient force for moving the toggle mechanism 36 against the action of spring 52 to thereby move the lever 48 which moves the ball 18 to the right to open up 70 the jet 16 to permit fuel to flow therethrough. Sufficient power is also provided to actuate the indicating mechanism. The actuation of the device is brought about by the difference in pressure between the up-stream and down-stream 75

sides of the jet 16. A slightly higher pressure exists on the up-stream side of the jet 16 and tends to move the diaphragm 20 to the right, as shown in Fig. 5, to a position comparable with the position shown in Fig. 6, depending upon the amount of fluid that is actually flowing to satisfy the demands of the internal combustion engine being tested.

The movement of the diaphragm 20 into the downstream chamber 22 is opposed by the spring 52 through the toggle 36. As the diaphragm 20 moves to the right in Fig. 5, the effective area of the diaphragm is reduced so that the force resulting from the application of pressure in the up-stream chamber 21 is reduced. Consequently it is desirable to reduce the force exerted by the spring 52 in opposition to the diaphragm. This is accomplished by the toggle mechanism which I employ. The spring 52 tends to pull the lever 37 toward the diaphragm 20. When the toggle is disposed so that the toggle joint is substantially to one side of a line between the pivot points of the free ends of the two toggle arms, the spring also exerts a force through the arm 38 tending to force both arms toward the diaphragm. The downward and lateral offsetting of point of connection 55 of the spring to the toggle arm 38 of course decreases the pivotal moment exerted on that toggle arm by spring 52 as compared to the moment exerted on toggle arm 37. As the diaphragm moves rearwardly from the position of Fig. 5 toward the position of Fig. 6, it is obvious that the toggle arm 38 approaches parallelism with the spring, hence the effect of spring 52 tending to rotate arm 38 in clockwise direction diminishes. Due to the greater lever arm provided by arm 51 on toggle arm 37, the predominant force on the diaphragm is always exerted by toggle arm 37. As the diaphragm moves rearwardly, the proportionate effect of the toggle arm 37 on the diaphragm becomes greater even though the total resultant force exerted on the diaphragm becomes less. Should the arm 38 become parallel with spring 52, as pointed out above, the effect of arm 38 would be nil. Arm 37 continually urges the diaphragm to the left, but the connection of spring 52 to toggle arm 38 insures that the resultant of the forces exerted on the diaphragm by the two toggle arms decreases as the toggle joint is broken away from the diaphragms.

It will be apparent that the force exerted by the spring in opposition to the diaphragm must be very slight and that friction must be substantially eliminated from the operation of the device. I accomplish this by utilizing the strap members as the connections and thereby substantially eliminate all friction. The mechanism is entirely floating as will be apparent and exerts substantially no friction producing forces against the bearings.

I make the chambers 21 and 22 restricted so that the device can be used practically in connection with the testing of the average internal combustion engine used in automobiles or the like. The restricted chambers 21 and 22 can be filled by the fuel supply system of the automobile before the supply of fuel in the carburetor is exhausted so that the apparatus can be simply and easily connected in the fuel line and the car started and the test made without the necessity for resorting to a filling of the device before testing. The restricted passage 23 dampens the action of the diaphragm and eliminates rapid fluctuations of the indicating device, which is

particularly valuable when tests are being made on the open road. When testing on the floor where vibrations are at a minimum and where it may be desirable to have a more sensitive response, the valve controlled by the knob 32 may be opened by turning that knob.

It will be apparent that the meter measures in reality the quantity of fuel flowing through the meter for a given period of time. I have so arranged the indicating device that in road testing a vehicle it is possible to determine and read directly the number of miles obtained for each gallon of fuel at a given speed. My adjusting device on the hand operated mechanism makes such a reading possible. By adjusting the cam 107 it is possible to adjust the position of the link 82 on the lever 81 so that if, for example, the fuel is flowing at the rate of four gallons per hour, the hand 15 at forty miles an hour will indicate that ten miles are obtained for each gallon of fuel used. If the speed happens to be twenty miles an hour, the mechanism is adjusted and the hand will indicate that five miles per gallon are being obtained.

Having thus described my invention, what I claim as new and desire to secure by Letters Patent is:

1. In an apparatus of the class described, the combination of a casing, a main fluid passage for the fluid to be metered, a variable orifice in said passage comprising a tapered jet with its restricted portion up-stream and a ball movable into and out of said tapered jet, said ball being mounted on a resilient wire member, an operating diaphragm dividing the casing into a restricted up-stream chamber and a restricted down-stream chamber, a restricted passage extending from the main fluid passage up-stream from said variable orifice to said up-stream chamber, and a passage extending from the down-stream chamber to the main fluid passage down-stream from said variable orifice, said casing having an opening therethrough into said down-stream chamber, a pivoted lever having its pivot point lying in the plane of said opening and extending outside said casing, through said opening, through said down-stream chamber, and across said operating diaphragm, said lever carrying said resilient wire member, a second diaphragm closing the opening in said casing and sealed to said lever at its pivot point, means connecting said operating diaphragm to said lever whereby movement of said operating diaphragm into said down-stream chamber moves said lever to increase the size of said variable orifice, and a spring tending to oppose the movement of the operating diaphragm into said down-stream chamber, and means operatively connecting said spring to said diaphragm so arranged that the effective force of the spring in opposition to the movement of the diaphragm is reduced during the movement of the operating diaphragm into the down-stream chamber, and indicating apparatus and means connecting said lever at a point outside said casing to said indicating apparatus, said operating diaphragm being of a size sufficient to permit utilization of the differential pressure of the flow of the fluid through said main fluid passage to permit direct operation of the variable orifice by said diaphragm without substantial pressure loss in the flow to be metered.

2. In an apparatus of the class described, the combination of a casing, a main fluid passage for the fluid to be metered, a variable orifice in

said passage, an operating diaphragm dividing the casing into a restricted up-stream chamber and a restricted down-stream chamber, a restricted passage extending from the main fluid 5 passage up-stream from said variable orifice to said up-stream chamber, and a passage extending from the down-stream chamber to the main fluid passage down-stream from said variable orifice, said casing having an opening there- 10 through into said down-stream chamber, a pivoted lever having its pivot point lying in the plane of said opening and extending outside said casing, through said opening, through said down-stream chamber, and across said operating dia- 15 phragm, and means connecting said lever operatively to said variable orifice to control the size thereof, a second diaphragm closing the opening in said casing and sealed to said lever at its pivot point, means connecting said oper- 20 ating diaphragm to said lever whereby movement of said operating diaphragm into said down-stream chamber moves said lever to increase the size of said variable orifice, and a spring tending to oppose the movement of the 25 operating diaphragm into said down-stream chamber, and means operatively connecting said spring to said diaphragm so arranged that the effective force of the spring in opposition to the movement of the diaphragm is reduced during 30 the movement of the operating diaphragm into the down-stream chamber, and indicating apparatus and means connecting said lever at a point outside said casing to said indicating apparatus, said operating diaphragm being of a size suffi- 35 cient to permit utilization of the differential pressure of the flow of the fluid through said main fluid passage to permit direct operation of the variable orifice by said diaphragm without substantial pressure loss in the flow to be metered.

3. In an apparatus of the class described, the combination of a casing, a main fluid passage for the fluid to be metered, a variable orifice in said passage, an operating diaphragm dividing the casing into an up-stream chamber and a 40 down-stream chamber, a passage extending from the main fluid passage up-stream from said variable orifice to said up-stream chamber, and a passage extending from the down-stream chamber to the main fluid passage down-stream from said variable orifice, said casing having an opening therethrough into said down-stream chamber, a pivoted lever having its pivot point lying in the plane of said opening and extending outside said casing, through said opening, through 45 said down-stream chamber, means connecting said lever operatively to said variable orifice to control the size thereof, a second diaphragm closing the opening in said casing and sealed to said lever at its pivot point, means connect- 50 ing said operating diaphragm to said lever whereby movement of said operating diaphragm into said down-stream chamber moves said lever to increase the size of said variable orifice, and a spring tending to oppose the movement of the 55 operating diaphragm into said down-stream chamber, and means operatively connecting said spring to said diaphragm so arranged that the effective force of the spring in opposition to the movement of the diaphragm is reduced during 60 the movement of the operating diaphragm into the down-stream chamber, and indicating apparatus and means connecting said lever at a point outside said casing to said indicating apparatus, said operating diaphragm being of a size suffi- 65 cient to permit utilization of the differential 70 pressure of the flow of the fluid through said main fluid passage to permit direct operation of the variable orifice by said diaphragm without substantial pressure loss in the flow to be metered.

4. In an apparatus of the class described, the combination of a casing, a main fluid passage for the fluid to be metered, a variable orifice in said passage, an operating diaphragm dividing the casing into a restricted up-stream chamber and a restricted down-stream chamber, a restricted passage extending from the main fluid 75 passage up-stream from said variable orifice to said up-stream chamber, and a passage extending from the down-stream chamber to the main fluid passage down-stream from said variable orifice, said casing having an opening there-

pressure of the flow of the fluid through said main fluid passage to permit direct operation of the variable orifice by said diaphragm without substantial pressure loss in the flow to be metered.

4. In an apparatus of the class described, the combination of a casing, a main fluid passage for the fluid to be metered, a variable orifice in said passage, an operating diaphragm dividing the casing into a restricted up-stream chamber and a restricted down-stream chamber, a restricted passage extending from the main fluid passage up-stream from said variable orifice to said up-stream chamber, and a passage extending from the down-stream chamber to the main fluid passage down-stream from said variable orifice, a spring tending to oppose the movement of the operating diaphragm into said down-stream chamber, and means operatively connecting said spring to said diaphragm so arranged that the effective force of the spring in opposition to the movement of the diaphragm is reduced during the movement of the operating diaphragm into the down-stream chamber, and indicating apparatus, and means connecting said operating diaphragm to said variable orifice 20 for controlling the size thereof and to said indicating apparatus whereby the amount of fluid flowing will be indicated, said operating diaphragm being of a size sufficient to permit utilization of the differential pressure of the flow 30 of the fluid through said main fluid passage to permit direct operation of the variable orifice by said diaphragm without substantial pressure loss in the flow to be metered.

5. In an apparatus of the class described, the combination of a casing, a main fluid passage for the fluid to be metered, a variable orifice in said passage, an operating diaphragm dividing the casing into an up-stream chamber and a down-stream chamber, a passage extending from the main fluid passage up-stream from said variable orifice to said up-stream chamber, and a passage extending from the down-stream chamber to the main fluid passage down-stream from said variable orifice, a spring tending to oppose the movement of the operating diaphragm into said down-stream chamber, and means operatively connecting said spring to said diaphragm so arranged that the effective force of the spring in opposition to the movement of the diaphragm is reduced during the movement of the operating diaphragm into the down-stream chamber, and indicating apparatus, and means connecting said operating diaphragm to said variable orifice for controlling the size thereof and to said indicating apparatus whereby the amount of fluid flowing will be indicated, said operating diaphragm being of a size sufficient to permit utilization of the differential pressure of the flow of the fluid through said main fluid passage to permit direct 60 operation of the variable orifice by said diaphragm without substantial pressure loss in the flow to be metered.

6. In an apparatus of the class described, the combination of a casing, a main fluid passage for the fluid to be metered, a variable orifice in said passage, an operating diaphragm dividing the casing into a restricted up-stream chamber and a restricted down-stream chamber, a restricted passage extending from the main fluid 70 passage up-stream from said variable orifice to said up-stream chamber, and a passage extending from the down-stream chamber to the main fluid passage down-stream from said variable orifice, said casing having an opening there-

through into said down-stream chamber, a pivoted lever having its pivot point lying in the plane of said opening and extending outside said casing, through said opening, through said down-stream chamber, and across said operating diaphragm, means connecting said lever operatively to said variable orifice to control the size thereof, a second diaphragm closing the opening in said casing and sealed to said lever at its pivot point, 10 means connecting said operating diaphragm to said lever whereby movement of said operating diaphragm into said down-stream chamber moves said lever to increase the size of said variable orifice, and a spring tending to oppose the movement 15 of the operating diaphragm into said down-stream chamber, and means operatively connecting said spring to said diaphragm, and indicating apparatus and means connecting said lever at a point outside said casing to said indicating apparatus, said operating diaphragm being of a size sufficient to permit utilization of the differential pressure of the flow of the fluid through said main fluid passage to permit direct 20 operation of the variable orifice by said diaphragm 25 without substantial pressure loss in the flow to be metered.

7. In an apparatus of the class described, the combination of a casing, a main fluid passage for the fluid to be metered, a variable orifice 30 in said passage, an operating diaphragm dividing the casing into an up-stream chamber and a down-stream chamber, a passage extending from the main fluid passage up-stream from said variable orifice to said up-stream chamber, and 35 a passage extending from the down-stream chamber to the main fluid passage down-stream from said variable orifice, said casing having an opening therethrough into said down-stream chamber, a pivoted lever having its pivot point 40 lying in the plane of said opening, and extending outside said casing, through said opening, through said down-stream chamber, means connecting said lever operatively to said variable orifice to control the size thereof, a second diaphragm 45 closing the opening in said casing and sealed to said lever at its pivot point, means connecting said operating diaphragm to said lever whereby movement of said operating diaphragm into said down-stream chamber moves said lever to increase the size of said variable orifice, and a 50 spring tending to oppose the movement of the operating diaphragm into said down-stream chamber, and means operatively connecting said spring to said diaphragm, and indicating apparatus 55 and means connecting said lever at a point outside said casing to said indicating apparatus, said operating diaphragm being of a size sufficient to permit utilization of the differential pressure of the flow of the fluid through 60 said main fluid passage to permit direct operation of the variable orifice by said diaphragm without substantial pressure loss in the flow to be metered.

8. In an apparatus of the class described, the combination of a casing, a main fluid passage for the fluid to be metered, a variable orifice in said passage, an operating diaphragm dividing the casing into a restricted up-stream chamber and a restricted down-stream chamber, a restricted 65 passage extending from the main fluid passage up-stream from said variable orifice to said up-stream chamber, and a passage extending from the down-stream chamber to the main fluid passage down-stream from said variable orifice, a spring tending to oppose the movement of the 70

operating diaphragm into said down-stream chamber, and means operatively connecting said spring to said diaphragm, and indicating apparatus and means connecting said operating diaphragm to said variable orifice for controlling the size thereof and to said indicating apparatus whereby the amount of fluid flowing will be indicated, said operating diaphragm being of a size sufficient to permit utilization of the differential pressure of the flow of the fluid through 10 said main fluid passage to permit direct operation of the variable orifice by said diaphragm without substantial pressure loss in the flow to be metered.

9. In an apparatus of the class described, the combination of a main passage for the fluid to be metered, a casing, a diaphragm dividing the casing into an up-stream chamber and a down-stream chamber, a variable orifice in said main passage, a connection from said up-stream chamber to said main fluid passage 20 up-stream from said variable orifice, a connection from said down-stream chamber to said main fluid passage down-stream from said variable orifice, means for exerting spring pressure opposed to movement of said diaphragm into 25 the down-stream chamber, said spring pressure decreasing as the diaphragm advances into said chamber whereby the diminishing of the effective area of the diaphragm is compensated for, comprising a toggle having the free end of its first 30 arm pivoted on a fixed pivot and having the free end of its second arm fastened to means disposed to hold said end against movement around the pivot of the free end of the first toggle arm but permitting movement of the free end of the second toggle arm to or away from said pivot point, an arm extending from the side of one of said toggle arms opposite to the side of the toggle from which its force is exerted, and a spring connected to the other of said toggle arms at a point spaced from the joint of the toggle and to said extending arm at a point spaced from its toggle arm, means connecting the toggle and the diaphragm whereby the force exerted by the spring may be transferred to 40 the diaphragm in opposition to movement of the diaphragm toward the toggle under the force of fluid flowing through the apparatus, and means for operatively connecting said toggle to said variable orifice to control the variations 45 thereof, an indicating apparatus, and means for operatively connecting said toggle to said indicating apparatus whereby the rate of fluid flow through the apparatus will be indicated by said indicating apparatus.

10. In an apparatus of the class described, the combination of a main passage for the fluid to be metered, a casing, a diaphragm dividing the casing into an up-stream chamber and a down-stream chamber, a variable orifice in said main passage, a connection from said up-stream chamber to said main fluid passage up-stream from said variable orifice, a connection from said down-stream chamber to said main fluid passage down-stream from said variable orifice, means for exerting spring pressure opposed to movement of said diaphragm into the down-stream chamber, said spring pressure decreasing as the diaphragm advances into said chamber whereby the diminishing of the effective area of the diaphragm is compensated for, comprising a toggle having the free end of its first arm pivoted on a fixed pivot and having the free end of its second arm fastened to means disposed to hold said end against movement around 55

the pivot of the free end of the first toggle arm but permitting movement of the free end of the second toggle arm to or away from said pivot point, an arm extending from the side of one of said toggle arms opposite to the side of the toggle from which its force is exerted, and a spring connected to the other of said toggle arms at a point spaced from the joint of the toggle and to said extending arm at a point spaced from its toggle arm, means connecting the toggle and the diaphragm whereby the force exerted by the spring may be transferred to the diaphragm in opposition to movement of the diaphragm toward the toggle under the force of fluid flowing through the apparatus, and means to control the variations of the variable orifice under control of the position of the diaphragm, an indicating apparatus and means for controlling said indicating apparatus under control of the position of the variable orifice whereby the rate of flow of fluid through the apparatus will be indicated by said indicating apparatus.

11. The combination of a movable member, means for exerting spring pressure against said member, said spring pressure decreasing as said member advances toward said means for exerting spring pressure, comprising a toggle having the free end of its first arm pivoted on a fixed pivot and having the free end of its second arm fastened to means disposed to hold said end against movement around the pivot of the free end of said first toggle arm but permitting movement of the free end of the second toggle arm to or away from said pivot point, an arm extending from the side of one of said toggle arms opposite from the direction in which the toggle exerts its force, and a spring connected to the other of said toggle arms at a point spaced from the joint of the toggle and spaced from the axis of said toggle arm on the side of the toggle opposite from said extending arm and to said extending arm at a point spaced from its toggle arm, whereby the effective length of the spring is controlled as the toggle positions change, and means connecting the toggle and the movable member whereby the force exerted by the spring may be transferred to the movable member.

12. The combination of a movable member, means for exerting spring pressure against said member, said spring pressure decreasing as said member advances toward said means for exerting spring pressure, comprising a toggle having the free end of its first arm pivoted on a fixed pivot and having the free end of its second arm fastened to means disposed to hold said end against movement around the pivot of the free end of said first toggle arm but permitting movement of the free end of the second toggle arm to or away from said pivot point, an arm extending from the side of one of said toggle arms opposite from the direction in which the toggle exerts its force, a spring connected to the other of said toggle arms at a point spaced from the joint of the toggle and to said extending arm at a point spaced from its toggle arm, and means connecting the toggle and the movable member whereby the force exerted by the spring may be transferred to the movable member.

13. In an apparatus of the class described, means for exerting spring pressure against a movable device the force produced by the movement of which varies as it advances, said spring pressure varying as the device advances, where-

by the variable force exerted by the device is compensated for, comprising a toggle having the free end of its first arm pivoted on a fixed pivot and having the free end of its second arm fastened to means disposed to hold said end against movement around the pivot of the free end of the first toggle arm but permitting movement of the free end of the second toggle arm to or away from said pivot point, an arm extending from the side of one of said toggle arms opposite the device, and a spring connected to the other of said toggle arms at a point spaced from the joint of the toggle and to said extending arm at a point spaced from its toggle arm, and means connecting the toggle and the device whereby the force exerted by the spring may be transferred to the device in opposition to movement of the device toward the toggle.

14. In an apparatus of the class described, means for exerting spring pressure against a movable device the force exerted by the movement of which varies as it advances, said spring pressure varying as the device advances, whereby the variable force exerted by the device is compensated for, comprising a toggle having the free end of its first arm pivoted on a fixed pivot and having the free end of its second arm fastened to means disposed to hold said end against movement around the pivot of the free end of the first toggle arm but permitting movement of the free end of the second toggle arm to or away from said pivot point, an arm extending from the side of one of said toggle arms opposite the device, and a spring connected to the other of said toggle arms at a point spaced from the joint of the toggle and located between the device and a line connecting the free ends of said toggle arms and to said extending arm at a point spaced from its toggle arm whereby the effective length of the spring is controlled as the toggle positions change, and means connecting the toggle and the device whereby the force exerted by the spring may be transferred to the device in opposition to movement of the device toward the toggle.

15. The combination of a movable member, means for exerting controlled spring pressure against movement of said member, comprising a toggle having the free end of its first arm pivoted on a fixed pivot and having the free end of its second arm fastened to means disposed to hold said end against movement around the pivot of the free end of said first toggle arm but permitting movement of the free end of the second toggle arm to or away from said pivot point, an arm extending from the side of one of said toggle arms, and a spring connected to the other of said toggle arms at a point spaced from the joint of the toggle and to said extending arm at a point spaced from its toggle arm, the joint of the toggle comprising a curved member on one toggle arm lying in contact with the other toggle arm and a flexible member fastened on said curved member and extending therearound and between said member and the adjacent toggle arm and fastened to the other toggle arm, and means connecting the toggle and movable member whereby the force exerted by the spring may be transferred to the movable member.

16. The combination of a movable member, means for exerting controlled spring pressure against movement of said member, comprising a toggle having the free end of its first arm pivoted on a fixed pivot and having the free end of its second arm fastened to means dis-

posed to hold said end against movement around the pivot of the free end of said first toggle arm but permitting movement of the free end of the second toggle arm to or away from said pivot point, an arm extending from the side of one of said toggle arms, and a spring connected to the other of said toggle arms at a point spaced from the joint of the toggle and to said extending arm at a point spaced from its toggle arm, the 5 joint of the toggle comprising a cam member on one toggle arm lying in contact with the other toggle arm and a flexible member fastened on said cam member and extending therearound and between said member and the adjacent toggle arm and fastened to the other toggle arm, and means connecting the toggle and movable member whereby the force exerted by the spring may be transferred to the movable member.

17. The combination of a movable member, 20 means for exerting controlled spring pressure against movement of said member, comprising a toggle having the free end of its first arm pivoted on a fixed pivot and having the free end of its second arm fastened to means disposed to hold 25 said end against movement around the pivot of the free end of said first toggle arm but permitting movement of the free end of the second toggle arm to or away from said pivot point, an arm extending from the side of one of said toggle arms opposite said movable member, and a spring 30 connected to the other of said toggle arms at a point spaced from the joint of the toggle and to said extending arm at a point spaced from its toggle arm, the joint of said toggle comprising a pair of opposed cam surfaces shaped to control 35 the spring pressure against the movable member, and a flexible member fastened at the end of one cam and extending between the cams and fastened to the opposite end of the opposed cam 40 in a manner to transmit the force of the spring, and means connecting the toggle and the movable member whereby the force exerted by the spring may be transferred to the movable member.

18. In an apparatus of the class described, a 45 toggle joint and spring mechanism for opposing the movement of a movable member comprising a first toggle arm having a fixed pivot, a second toggle arm having its free end anchored against movement about the pivot of the first toggle arm 50 by a thin metal strap which permits movement of the free end of the second toggle arm to or away from the pivot of the first toggle, an arm extending from one of said toggle arms, and a spring connecting said extending arm and the 55 other toggle arm and connections between the spring and the extending arm and toggle arm comprising thin metal straps.

19. In an apparatus of the class described, a 60 toggle joint and spring mechanism for opposing the movement of a movable member comprising a first toggle arm having a fixed pivot, a second toggle arm having its free end anchored against movement about the pivot of the first toggle by means permitting movement of the free end of the 65 second toggle arm to or away from the pivot of the first toggle, an arm extending from one of said toggle arms, and a spring connecting said extending arm and the other toggle arm and connections between the spring and the extending arm and toggle arm comprising thin metal straps.

20. In an apparatus of the class described, a 70 toggle joint and spring mechanism for opposing the movement of a movable member comprising a first toggle arm having a fixed pivot, a sec-

ond toggle arm having its free end anchored against movement about the pivot of the first toggle arm by a flexible member which permits movement of the free end of the second toggle arm to or away from the pivot of the first toggle, 5 an arm extending from one of said toggle arms, and a spring connecting said extending arm and the other toggle arm and connections between the spring and the extending arm and toggle arm comprising flexible members.

21. In an apparatus of the class described, the combination of a casing, a main fluid passage for the fluid to be metered, a variable orifice in said passage, an operating diaphragm dividing the casing into an up-stream chamber and a down-stream chamber, said operating diaphragm being of a size sufficient to permit utilization of the differential pressure of the flow of the fluid through said main fluid passage to permit direct operation of the variable orifice by said diaphragm 20 without substantial pressure loss in the flow to be metered, a passage extending from the main fluid passage up-stream from the variable orifice to said up-stream chamber, and a passage extending from the down-stream chamber to the main fluid 25 passage down-stream from said variable orifice, spring means tending to oppose movement of the operating diaphragm into said down-stream chamber comprising a toggle having the free end of its first arm pivoted on a fixed pivot and having the free end of its second arm fastened to 30 means disposed to hold said end against movement around the pivot of the free end of said first toggle arm by permitting movement of the free end of the second toggle arm to or away from 35 said pivot point, an arm extending from the side of one of said toggle arms and a spring connected to the other of said toggle arms at a point spaced from the joint of the toggle and to said extending arm at a point spaced from its toggle arm, and 40 means connecting the diaphragm and said toggle in such a manner that the action of the spring opposes the movement of the diaphragm into the down-stream chamber and compensates for the decrease in the effective area of the diaphragm as 45 it advances into said chamber, and means controlled by said diaphragm for controlling said variable orifice.

22. In an apparatus of the class described, the combination of a main passage for the fluid to be metered, a casing, a diaphragm dividing the casing into an up-stream chamber and a down-stream chamber, a variable orifice in said main passage, a connection from said up-stream chamber to said main fluid passage up-stream from said variable orifice, a connection from said down-stream chamber to said main fluid passage down-stream from said variable orifice, means for exerting spring pressure opposed to movement of said diaphragm into the down-stream chamber, said spring pressure decreasing as the diaphragm advances into said chamber whereby the diminishing of the effective area of the diaphragm is compensated for, comprising a toggle having the free end of its first arm pivoted on a fixed pivot and having the free end of its second arm fastened to 60 means disposed to hold said end against movement around the pivot of the free end of the first toggle arm but permitting movement of the free end of the second toggle arm to or away from 65 said pivot point, an arm extending from the side of one of said toggle arms opposite to the side of the toggle from which its force is exerted, and a spring connected to said extending arm at a point spaced from its toggle arm tending to force said 70

toggle toward said diaphragm, means connecting the toggle and the diaphragm whereby the force exerted by the spring may be transferred to the diaphragm in opposition to movement of the diaphragm toward the toggle under the force of fluid flowing through the apparatus, and means to control the variations of the variable orifice under control of the position of the diaphragm, an indicating apparatus and means for controlling 5 said indicating apparatus under control of the position of the variable orifice whereby the rate of flow of fluid through the apparatus will be indicated by said indicating apparatus.

23. In an apparatus of the class described, the combination of a main passage for the fluid to be metered, a casing, a diaphragm dividing the casing into an up-stream chamber and a down-stream chamber, a variable orifice in said main passage, a connection from said up-stream chamber to said main fluid passage up-stream from said variable orifice, a connection from said down-stream chamber to said main fluid passage down-stream from said variable orifice, means for exerting spring pressure opposed to movement of 10 said diaphragm into the down-stream chamber, said spring pressure decreasing as the diaphragm advances into said chamber whereby the diminishing of the effective area of the diaphragm is compensated for, comprising a toggle having the 15 free end of its first arm pivoted on a fixed pivot and having the free end of its second arm fastened to means disposed to hold said end against movement around the pivot of the free end of the first toggle arm but permitting movement of the 20 free end of the second toggle arm to or away from said pivot point, and a spring tending to force said toggle toward said diaphragm, means connecting the toggle and the diaphragm whereby the force exerted by the spring may be transferred to the 25 diaphragm in opposition to movement of the diaphragm toward the toggle under the force of fluid flowing through the apparatus, and means to control the variations of the variable orifice under control of the position of the diaphragm, an indicating apparatus and means for controlling said indicating apparatus under control of the position of the variable orifice whereby the rate of flow of fluid through the apparatus will be indicated by said indicating apparatus.

24. The combination of a movable member, means for exerting spring pressure against said member, said spring pressure decreasing as said member advances toward said means for exerting spring pressure, comprising a toggle having the 30 free end of its first arm pivoted on a fixed pivot and having the free end of its second arm fastened to means disposed to hold said end against movement around the pivot of the free end of said first toggle arm but permitting movement of the 35 free end of the second toggle arm to or away from said pivot point, an arm extending from the side of one of said toggle arms opposite from the direction in which the toggle exerts its force, and a spring connected to said extending arm at a point 40 spaced from its toggle arm tending to force said toggle toward said movable member, whereby the effective length of the spring is controlled as the toggle positions change, and means connecting the toggle and the movable member whereby the 45 force exerted by the spring may be transferred to the movable member.

25. In an apparatus of the class described, means for exerting spring pressure resisting movement of a pressure actuated device the 50 force of whose movement decreases as the de-

vice advances, said spring pressure decreasing as the device advances whereby the diminishing of the force exerted by the device is compensated for, comprising a toggle having the free end of its first arm pivoted on a fixed pivot and having the free end of its second arm fastened to means disposed to hold said end against movement around the pivot of the free end of the first toggle arm but permitting movement of the free end of the second toggle arm to or away from 5 said pivot point, and a spring tending to urge said toggle against said device, and means connecting the toggle and the device whereby the force exerted by the spring may be transferred to the device in opposition to movement of the 10 device toward the toggle.

26. The combination of a movable member, means for exerting controlled spring pressure against movement of said member, comprising a toggle having the free end of its first arm pivoted on a fixed pivot and having the free end of its second arm fastened to means disposed to hold said end against movement around the pivot of the free end of said first toggle arm but permitting movement of the free end of the second toggle arm to or away from 15 said pivot point, and a spring tending to force said toggle in opposition to movement of said movable member, the joint of the toggle comprising a curved member on one toggle arm lying in contact with 20 the other toggle arm and a flexible member fastened on said curved member and extending therearound and between said member and the adjacent toggle arm and fastened to the other toggle arm, and means connecting the toggle 25 and movable member whereby the force exerted by the spring may be transferred to the movable member.

27. In an apparatus of the class described, means for opposing movement of a device movable with varying force in a given direction in 30 such manner that the opposition to movement likewise varies as the device moves in said direction, comprising a pair of toggle arms having adjacent ends thereof connected for movement with the device and the remote ends thereof restrained and provided with extension members on the opposite side of the toggle arms from the device, resilient tension means connected between said extension members, said 35 tension means being connected to one of said extension members at a point farther removed from its toggle arm than the point of connection of the tension means to the other member is removed from its toggle arm, whereby said tension means exerts a greater moment on one of said toggle arms than on the other, and means for connecting said device to said toggle arms for actuation of the latter in response to movement of the device, at least one of said toggle 40 arms approaching parallelism with said tension means during said actuation to vary the resultant effort exerted by said arms on the device in accordance with the varying force exerted by the device.

28. In an apparatus of the class described, means for opposing movement of a device movable with varying force in a given direction in 45 such manner that the opposition to movement likewise varies as the device moves in said direction, comprising a pair of toggle arms having adjacent ends thereof connected for movement with the device and the remote ends thereof restrained and provided with extension members, resilient tension means connected between said 50

extension members to exert a greater moment on one of said toggle arms than on the other, and means for connecting said device to said toggle arms for actuation of the latter in response to movement of the device, at least one of said toggle arms during said actuation ap-

proaching a position wherein the rotative effect exerted thereon by said tension means is nullified, to diminish the resultant effort exerted by said arms on the device in accordance with the diminished force exerted by the device. 5

FRANK W. THOMAS.
